FLUID DISCHARGE NOZZLE

Antonio Fernando de la Calle, Mexico City,
Mexico

Application October 31, 1940, Serial No. 363,655

3 Claims. (Cl. 225—6)

This invention relates to fluid discharge nozzles, and particularly to devices of this type and kind for use in dispensing various viscous and carbonated fluids which are susceptible to the formation of foam upon the discharge thereof into a receiving receptacle, but more particularly the invention relates to nozzles adaptable for use in the discharge of draft beer; and the object of the invention is to provide a nozzle having means for spreading the fluid or liquid in thin film-like layers facilitating the quick and easy breaking up of the gas bubbles and thereby substantially eliminating the formation of foam in dispensing the fluid or liquid in a receptacle or container; and with these and other objects in view, the invention consists in a device of the class and for the purpose specified, which is simple in construction, efficient in use, and which is constructed as more fully hereinafter described and claimed.

The invention is fully disclosed in the following specification, of which the accompanying drawing forms a part, in which the separate parts of my invention are designated by suitable reference characters in each of the views, and in which:

Fig. 1 is a longitudinal sectional view through one form of nozzle which I employ.

Fig. 2 is a section on the line 2—2 of Fig. 1.

Fig. 3 is a view similar to Fig. 1 showing another adaptation of the invention.

Fig. 4 is a view similar to Figs. 1 and 3 showing another modification.

Fig. 5 is a section on the line 5—5 of Fig. 4; and

Fig. 6 is a view similar to Figs. 1, 3 and 4 showing another form of construction.

In dispensing liquids or fluids of various types and kinds, as for an example in dispensing draft beer, the formation of excessive amount of foam in the receiving receptacle has caused considerable waste, inconvenience and moreover, considerable delay in service by reason of the necessity of having to refill the glass or receptacle into which the beer has been dispensed. It is the object of my invention to provide a discharge nozzle for various types and kinds of foam-forming liquids or fluids to eliminate the objectionable features in the formation of such foam. In this connection, it must of course be understood that in the service of beer, the presence of a little foam, commonly referred to as "a head" on the beer, would be desirable, but this can be adjusted by the use of a nozzle which will control, by reason of its discharge passages, and film guiding surfaces, the amount of foam to be collected in a receptacle of predetermined size.

In the accompanying drawing, a few adaptations of the invention are disclosed, and in Figs. 1 and 2 is shown at 10 a discharge nozzle comprising a large casing portion 11 having contracted upper and lower ends 12 and 13. The end 12 terminates in a suitable pipe connection 14, whereas the end 13 terminates in a discharge spout 15. The nozzle 10 is of a built-up construction as will be apparent. Arranged in the upper end portion of the casing 11 adjacent the contracted portion 12, is a cup-shaped member 16, the depending side walls 17 of which are arranged in spaced relation to the walls of the casing 11 to form a narrow or restricted discharge passage 18. The cap 16 may be spaced in the casing by a series of ribs 19, note Fig. 2, which are welded or brazed in position, or any other method may be employed for spacing the cap 16 and securing the same in the casing. With the construction shown in Figs. 1 and 2, the fluid to be dispensed through the nozzle or discharge 10 will be guided as a thin layer or film along the inner surface 11a of the casing 11, thereby allowing the gas bubbles or at least the majority of these gas bubbles to break up and be discharged from the fluid; thus eliminating to a major degree, the formation of foam in a receptacle in the discharge of the fluid from the spout end 15 thereof.

In Fig. 3 of the drawing is illustrated another adaptation of the invention. In this structure the nozzle 10a comprises an elongated tube 20 beveled at its lower end as seen at 21 in forming the discharge spout. Arranged upon the upper end of the tube 20 is a coupling or header 22 in which the tube 20 is secured in the same manner as attaching the cap 16 to the casing 11 in Fig. 1. Within the tube 20 is arranged a cap 23 similar to the cap 16, thus forming in the resulting nozzle structure an inner thin discharge passage 24 similar to the passage 18, and an outer discharge passage 25. The header 22 also includes a pipe connection 26.

With the construction shown in Fig. 3, it will be apparent that a thin layer or film of the fluid will pass downwardly over both the inner surface 20a and the outer surface 20b of the tube 20, thus increasing the volume of the fluid dispensed from a nozzle of predetermined tubular size. It will be apparent, however, that the discharge as at 25 may be dispensed with where the question of volume is not a factor.

In Figs. 4 and 5 of the drawing is shown another adaptation of the invention wherein the nozzle 10b comprises a coupling end or header 27 having a pipe connection 28. Within the header

adjacent the discharge end thereof is disposed a grating 29 which forms a series of parallel openings 30, note Fig. 5. Supported centrally and longitudinally of these openings are a series of depending nozzle plates 31 which form between the opposed walls of the openings 30 and side walls of the header 21, a series of thin discharge passages 32, as is noted in Fig. 4 of the drawing. These passages will guide the fluid or liquid in thin layers or films upon both side surfaces of the nozzle plates 31, as will be apparent. It will also be understood that while the contour of the nozzle as shown in Figs. 4 and 5 of the drawing is represented as rectangular rather than round, this has been done simply to show that the particular cross sectional contour of the nozzle may be varied. However, the same principle of construction shown in Figs. 4 and 5 is applicable to nozzles of any cross sectional form.

In Fig. 6 of the drawing is shown a further adaptation of the invention where in addition to the idea of having a film traveling over a relatively large surface, the film or fluid may also be guided over a relatively restricted surface, such for example as rods or wires. In this construction, 10c represents the discharge nozzle comprising a casing 33 having a contracted end 34 terminating in a discharge spout 35; the upper end 36 of the casing being closed and having a pipe coupling 37. Within the casing 33 is arranged a cap 38 of the general construction of the cap 16 and positioned to form a discharge passage 39 between the periphery thereof and the inner surface of the casing 33, so that in this respect, the structure will operate substantially similar to the structure shown in Fig. 1. However, the structure is modified by providing in the top wall of the cap 38, a plurality of apertures 40 which may be arranged in any desired manner. Arranged in these apertures and extending downwardly through the casing 33, in the manner illustrated, are a plurality of rods, wires, or the like 41 which are spaced from the walls and the apertures 40 so as to provide for the collection of a film or layer of the fluid around the wires or rods 41 for the purposes stated. The wires or rods 41 are supported in connection with a plate 42 arranged above the cap 38 and supported in the casing 33 in the same manner as supporting the cap 38 therein, or in other words, in the manner of supporting the cap 16, to provide passages 43 at the periphery of the plate 42 so as to allow the fluid to extend to the apertures 40 as well as through the passage 39.

From the teachings in Figs. 4, 5 and 6, it will be apparent that by controlling the amount of surface over which a fluid may pass through the nozzle, the volume of fluid to be discharged through the nozzle can be controlled and at the same time the degree of foam elimination can also be controlled. It will also be apparent that the length of the various nozzles may be modified to suit different adaptations of the invention.

From the teachings in Figs. 4, 5 and 6, it will

generally speaking, the discharge devices may be said to comprise means for guiding a fluid in thin layers or films, thereby breaking up gas bubbles in the fluid prior to discharge of the fluid into a receiving receptacle and eliminating excessive formation of foam on the fluid dispensed into the receptacle.

Having fully described my invention, what I claim as new and desire to secure by Letters Patent, is:

1. A nozzle of the class described for discharging foaming liquids, said nozzle comprising a header having an inlet passage and a plurality of restricted outlet passages, means associated with

15 said outlet passages for conducting discharged liquid away from said passages, said discharge passages being circumferentially arranged in said header, said conducting means comprising a tubular member extending from said passages, and 20 said header having other circumferential passages arranged concentrically to said first named outlet passages, said concentric passages registering with opposed surfaces of said tubular member, thereby providing for the discharge of fluid 25 on both inner and outer surfaces of said member.

2. In a nozzle of the class described having an inlet passage and a tubular body forming a discharge passage, means associated with said tubular body for spreading a discharged fluid in a thin film on the walls of said tubular body, thereby providing for the liberation of free gas bubbles from said fluid, said last named means comprising a shallow cup-like member secured to said tubular body and spaced therefrom sufficiently to provide a narrow annular discharge passage between said tubular body and cup-like member, said cup-like member comprising a header arranged outwardly of said tubular body and having an enlarged passage forming the inlet passage of said nozzle, and said nozzle including another cup-like member arranged inwardly of and in closely spaced relation to said tubular body, thereby providing for the discharge of fluid along both inner and outer surfaces of said body.

3. A fluid discharge nozzle for dispensing liquids, said nozzle comprising a header having an inlet passage adapted to communicate with a fluid supply, elongated fluid conducting means of predetermined cross sectional contour associated with said header and extending vertically therefrom for conducting fluid from said header as a thin film having one surface contacting said means and the other surface exposed to permit liberation of free gas bubbles, said conducting means comprising a tubular body, a cup-like member arranged within said tubular body adjacent the upper end thereon, and means securing together said header, tubular body and last named member to form narrow discharge passages along both inner and outer surfaces of said tubular body.

ANTONIO FERNANDO DE LA CALLE.
